CIGARETTE PACKAGE

Louis M. Klein, Chicago, Ill., assignor to American
Pouch Corporation, a corporation of Illinois

Application July 21, 1938, Serial No. 220,477

1 Claim. (Cl. 206—41)

This invention relates to new and useful improvements in a cigarette package.

More specifically, the invention proposes the construction of a cigarette package characterized by a one piece Cellophane jacket for engaging entirely around a plurality of cigarettes in such a manner that the contents of the package may be viewed from all sides.

Heretofore, in the construction of cigarette jackets it has been impossible to view the contents of the package and further, a corner of the package is usually opened and cannot again be resealed. This permits drying out of the cigarettes if not used within a reasonable time.

Another object of this invention is the construction of a cigarette package which may be opened across its entire top instead of only one corner, and which may be re-folded and sealed air tight any number of times for preventing the cigarettes from drying out.

Still further it is proposed to provide a flap having a portion extending along one side of the jacket and upon which a tab for holding the flap in a closed position is mounted.

Still further it is proposed to provide a "tacky" substance upon the free edge of the tab for permitting the tab to be attached to the adjacent face of the jacket proper, and released therefrom any number of times for permitting the entire top of the jacket to be opened.

Still further it is proposed to provide an individual Cellophane or the like wrapper for each cigarette contained within the jacket.

Still further it is proposed to provide the ends of the individual wrappers with recessed areas engageable by complementary recessed areas formed in the ends of the cigarette jacket for selectively stationarily holding the cigarettes in position regardless of the number of cigarettes removed therefrom.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a perspective view of a cigarette package constructed in accordance with this invention.

Fig. 2 is a partial perspective view of the cigarette package showing the top thereof in the open position.

Fig. 3 is a developed view of the blank from which the jacket is formed.

Fig. 4 is a view similar to Fig. 1 but illustrating a modification of the invention.

Fig. 5 is a sectional view taken on the line 5—5 of Fig. 4.

Fig. 6 is a perspective view of one of the individual Cellophane wrappers per se.

The cigarette package, according to this invention, comprises a Cellophane or the like jacket 10 for holding a plurality of cigarettes 11 and which is adapted to be imprinted or encased with a package design. The Cellophane or the like jacket 10 is constructed of a single piece of Cellophane and is formed with a bottom portion 10a continuing at its sides into side portions 10b for the jacket 10. The ends of the bottom 10a are formed with bottom flaps 10c which are adapted to be extended vertically along the bottom ends of the cigarettes 11. The sides of the side portions 10b continue into side flaps 10d, two for each side of the jacket, and are adapted to be superimposed one upon the other and upon the bottom flaps 10c. The end flaps 10d are secured together in any conventional manner for holding the jacket 10 in its folded condition.

The side flaps 10d on one of the side portions 10b are formed with inwardly extending top flaps 10e which are adapted to be folded inwards and extended across the top ends of the cigarettes 11 as shown in Fig. 1. The upper ends of the side portions 10b are formed with inwardly extending top portions 10f which are normally extended in a superimposed position over the top ends of the cigarettes 11 and the top flaps 10e for completely closing the top end of the jacket. The top member 10f on the end opposite the top flaps 10e is formed with a flap 10g which is adapted to extend downwards along one side of the cigarette jacket 10 as shown in Fig. 1. The flap 10g is formed with a tab 12 which has one of its ends securely attached to the free end of the flap 10g. The free end of the tab 12 is formed with a "tacky" material 13 which permits the free end of the tab 12 to be attached to the adjacent face of the jacket 10 for maintaining the flap 10g in a position in which the top end of the cigarette jacket will be closed air tight. This tab 12 may be manually pulled from the adjacent face of the cigarette jacket to free the flap 10g to permit the top of the cigarette jacket to be entirely opened as shown in Fig. 2. This permits the cigarettes to be easily withdrawn from the jacket, after which the flaps 10d and the top portions 10f may be returned to their normal position ex-

tended across the top of the jacket air tightly closing the same regardless of the number of times it has been opened.

5 A stiffening member 14 is attached to the outer face of the tab 12 and is securely maintained in position thereon for reinforcing this area to prevent the tab from being torn away from the flap 10^a and also prevent the flap from being torn as the tab 12 is manually pulled away from the adjacent face of the jacket 10.

10 This construction of a cigarette jacket permits the contents thereof to be easily viewed without opening the same, and also permits the jacket to be opened any number of times to permit 15 removal of the cigarettes and still permit the jacket to be sealed air tight after each opening to prevent drying of the cigarettes.

According to the modification of the invention shown in Figs. 4 and 5 the construction of the 20 cigarette package is similar to that previously described and distinguished therefrom by the inclusion of individual Cellophane or the like wrapper for each of the cigarettes, and a means for selectively stationarily holding the cigarettes in 25 position within the jackets. Each of the cigarettes 11 is inserted into a tubular Cellophane wrapper 15 which has one of its ends closed and the other of its ends provided with a cover 16 permitting the removal of the cigarette therefrom. The cover 16 is formed with a tab 16^a 30 for permitting the cover to be manually pulled away from the end of the tube 15 for opening the same to permit the cigarette 11 to be slipped therefrom.

35 The means for individually selectively stationarily holding the cigarettes in position within the jacket comprises inwardly extended recessed areas 17 formed in the ends of each of the tubular wrappers 15. The bottom 10^a of the jacket 10 and one of the top flaps 10^b of the jacket are also 40 formed with inwardly extending recessed areas 18 which are adapted to be selectively engaged into the recessed areas 17 formed in the ends of 45 the tubes 15 for holding the cigarettes in fixed

positions within the jacket 10 regardless of the number of cigarettes removed therefrom.

When the top members 10^b are opened the wrappers 15 may be removed therefrom to permit access to the cigarettes 11, and when the top 5 members 10^b are returned to their normal position the recesses 18 will engage into the recesses 17 formed in the top end of the tubular wrappers 15 for holding the cigarettes in fixed positions therein. In other respects this form of 10 the invention is similar to the previous form.

It is to be understood that the jacket may be sealed in any direction desired.

While I have illustrated and described the preferred embodiments of my invention, it is to be 15 understood that I do not limit myself to the precise constructions herein disclosed and the right is reserved to all changes and modifications coming within the scope of the invention as defined in the appended claim. 20

Having thus described my invention, what I claim is new, and desire to secure by United States Letters Patent is:

A cigarette package, comprising a jacket enclosing a plurality of cigarettes having a bottom 25 wall and an open top, a wrapper enclosing each of said cigarettes having closed ends formed with inwardly extending recesses, a plurality of inwardly extending projections formed on said bottom wall and engageable into the recesses 30 formed in one end of said wrappers, a top flap extending across the open top of said jacket, a second top flap extending across the top face of said flap and in a direction opposed to the direction in which said flap extends, a downwardly extending portion formed on said second top flap for extending along one side of said jacket, means for releasably securing said portion to said side for holding said flaps closed, and a plurality of inwardly extending projections formed on said 35 first top flap and engageable into said recesses 40 formed in the other end of said wrappers and cooperative with said projection for holding said wrappers stationary in position within said jacket.

LOUIS M. KLEIN.
